AXIAL FLOW FAN

Philip A. Sidell, Rock Island, Ill., assignor to
American Machine and Metals, Inc., East Mo-
line, Ill., a corporation of Delaware

Application May 15, 1943, Serial No. 487,090

6 Claims. (Cl. 170—173)

1

The present invention relates to fluid impelling devices and more in particular to axial flow fans of multi-part construction in which the parts may be readily and easily fabricated and assembled to provide the complete fan assemblies.

Among the objects of the present invention is to provide an axial flow fan which is rigid and rugged in its construction and in which the blades are mounted upon and secured to a centrally disposed blade supporting element such that the blades are in planes angularly disposed in respect to the plane of rotation of the supporting element.

A further object of the present invention is to provide a novel axial flow fan which is simple in construction, but which meets all operating conditions, and which attains a high degree of efficiency in its operation.

More particularly the present invention is grounded upon a desire to provide a suitable axial flow fan assembly in which the connection between the blades and the central supporting element is such as to secure increased strength and which more effectively resists the various stresses to which such blades are usually subjected.

As one of the principal objects the present invention contemplates a connection between the blades and the central supporting element which is formed by virtue of the provision of notches at the inner ends of the blades extending in the direction of the major axis thereof and which allows the marginal portions of the blade forming the slot to straddle the central supporting element and to be secured in such relation. More particularly the notched or slotted formation of the blades permits the blades to be disposed in their desired pitch relation to the plane of rotation of the fan, and provides for contacting relation of the marginal edges of the slot with the opposed faces of the central supporting element. The provision of the slotted formation for the blades with their line contact with the central supporting element lends itself admirably to the use of various means for connecting the blades to the central supporting element, which effectively resists centrifugal and radial stresses as well as bending moments at the root of the blades, and all of which stresses are carried by the attachment or fastening means in shear, thus greatly increasing the desirable structural characteristics of such an assembly as distinguished from the structures of the prior art.

Another object of the present invention is to provide a novel axial flow fan assembly in which

2

the connection between the blades and the central supporting element involves the use of notched blades straddling the said element, and which provides substantially extended line engagement between the same to greatly increase the strength of the resulting fan structure.

A further object of the present invention is to provide a novel connection between the blades and the central supporting element of an axial flow fan, in which the blades are formed with notches whereby the blades are adapted to straddle the said element and the marginal portions defining the slot or notch for the blades, are adapted to be offset in various angular relation to the blade itself to secure any desired line contact between the blades and element, thus assuring a rigid attachment of the blades to said element.

A still further object of the present invention is to provide a novel connection between the blades and the central supporting element of an axial flow fan involving the use of notches at the ends of the blades which can be varied as to their depth and formation to provide a connection between the blades and element which will effectively resist in shear, both at the top and bottom thereof, the bending moment to which the blades are subjected, and which holds the blades rigid against rotation or vibration about the axis thereof.

Still another object of the present invention is to provide a novel form of connection between the blades and a central supporting element of an axial flow fan involving the use of slots at the inner ends of the blades which may be of any desired formation to readily permit the manufacturer of such blades to provide for any variation in pitch of the said blades in the fan assembly.

Another object within the purview of the present invention is to provide a novel connection between the blades and a central supporting element of an axial flow fan involving the provision of slots at the ends of the blades, and in which the marginal portions defining the slots may be offset in respect to the blade in any desired manner to facilitate the connection of the blades to the element without the use of special fittings, but which lends itself admirably to the use of such fastening means as angular fittings, bolts, screws or welding.

A further desideratum of the present invention is to provide a simplified construction in which the marginal portions of the blades defining the slots may take any formation desired to

incorporate side, bottom or multiple pockets into the assembly and to secure multiple connections between the blades and the supporting element as well as facilitates attachment of adjacent blades together if so desired, all of which connections provide for greater rigidity in the fan assembly.

Another object of the invention is to provide a novel connection between fan blades and a supporting element that is narrower than the blades, such that the rigidity of the blades is secured both axially and tangentially of the supporting element and particularly on the diagonal of these two directions.

A still further object of the present invention is to provide an axial flow fan of multi-part construction in which the connection between the blades and a central supporting element is such as to minimize radial fluid flow and turbulence created thereby, thus securing maximum efficiency of operation of the said fan assembly.

More particularly the invention contemplates a connection such that portions of the fan blades in connected and assembled relation with a supporting element act as barriers preventing radial fluid flow in the assembly.

As an additional object, the present invention contemplates an axial flow fan of multi-part construction in which the said parts are connected to one another in such a manner as to facilitate protection of the fan after it is assembled against corrosion or rust, either by painting, spraying or plating.

Other objects, features, capabilities and advantages are comprehended by the invention, as will later appear and as are inherently possessed thereby.

Referring now to the drawings—

Figure 1 is a view in elevation of a fan assembly made in accordance with the present invention and having parts thereof broken away to more clearly disclose certain detailed construction thereof;

Figure 1A is an end view of a blade for the assembly of Figure 1 of the drawings;

Figure 1B is a view in side elevation of a blade for the assembly of Figure 1 of the drawings;

Figure 2 is a view partly in section and partly in side elevation of the fan assembly shown in Figure 1 and taken in the planes represented by line 2—2 of that figure;

Figure 3 is a view in elevation of a modified form of fan assembly made in accordance with the present invention and having parts broken away to disclose certain of the structure more in detail;

Figure 4 is a view partly in section and partly in side elevation of the fan assembly shown in Figure 3 and taken in the planes represented by line 4—4 of that figure;

Figure 5 is a fragmentary view in elevation of still another form of construction for a fan made in accordance with the present invention;

Figure 6 is an enlarged fragmentary view in elevation of a single blade and its associated support of the fan assembly shown in Figure 5 of the drawings;

Figure 7 is a fragmentary end view taken substantially in the plane represented by line 7—7 of Figure 6;

Figure 8 is a view in elevation of a further modified form of fan assembly made in accordance with the invention and having parts broken away to disclose certain parts of the structure more in detail; and

Figure 9 is a view partly in section and partly

in side elevation of the fan assembly shown in Figure 8 and taken in the plane represented by the line 9—9 of that figure.

Referring now more in detail to the drawings, one embodiment selected to illustrate the present invention is shown in Figures 1 and 2 as comprising an axial flow fan of multipart construction, comprising a plurality of blades 2 of similar construction mounted upon and secured to a central supporting element 4 which, in the present illustration, is formed from a member of substantially disc-like construction. Secured to the central portion of the member 4 is a bearing 6 whereby the fan impeller is adapted to be mounted upon and keyed or otherwise secured to a shaft 8, which may be the driving shaft of a motor or other source of power adapted to rotate the impeller about the axis of said shaft.

The present invention is primarily concerned with a suitable attachment for the blades to the central supporting member 4 which lends rigidity to the resulting assembly and which facilitates the ready manufacture and fabrication as well as the assembly of the component parts of the impeller at low cost. Such a connection involves the provision of slots 10 at the inner ends of these blades, whereby the marginal portions forming the slots are disposed in straddling relation to the periphery or circumference of the supporting element 4 and which provides for the connection of the blades to said element by means of welding or the like.

In the illustrative example of the invention as shown in Figures 1 and 2, the slot 10 diverges outwardly toward the inner end of the blades and is of a sufficient depth to provide marginal portions 12 and 14 which will provide a suitable connection between the blades and the central supporting element 4. In accordance with this disclosure the marginal portions 12 and 14 are bent in offset relation to the general plane of the blade to dispose their marginal edges defining the slot 10 in parallel planes, so that such marginal edges have substantially line contact with the outer radially extending faces 16 and 18 of the element 4. The formation of the slots is such that the marginal edges thereof are in substantial contact with the faces 16 and 18 both radially and circumferentially of the element 4 and in opposed relation to the longitudinal axis of the blades to assure rigidity of the assembled fan structure. It is to be noted, also, that the blades are so disposed that their working faces are angularly arranged with respect to the plane of rotation of the fan to provide the desired pitch therefor.

By virtue of the particular offset relation of the marginal portions 12 and 14 with respect to the general plane of the blades substantial support is provided for the blades to assure rigidity in the connection thereof to the supporting element 4, and which connections are adapted to resist in shear the various stresses and bending moments to which the blades are subjected. Furthermore, because of this slotted relation of the blades to the element 4, the blades can be readily fabricated to make possible any variation in the pitch of the fan blades with respect to the element 4 by the simple procedure of varying the particular formation for these slots. As clearly shown in the drawings, the blades are curved to approximate an aerofoil section from the outer end thereof to adjacent the inner end of the slot 10 so as to secure the advantages in efficiency which result from such formation in an impeller blade of this type.

In Figures 3 and 4 is disclosed a modified axial flow fan assembly made in accordance with the present invention, the same being of multi-part construction involving a plurality of blades 20 and a central supporting element 22, which latter element has the bearing 240 secured thereto, whereby the impeller may be suitably mounted upon and secured to a shaft, such as shaft 8 of the first described embodiment.

In this modified structure, the central supporting element 22 comprises two dished disc-like sections 24 and 26 formed with the outer complementary annular flanges such as 28, which are secured or fastened together as by means of spot-welding or the like, and provide a cylindrical-like hub as illustrated in the drawings. The connection between the blades 20 and this hub 22 conforms essentially to the connection disclosed in Figures 1 and 2 of the drawings, except that the said blades at their inner ends are formed with a notch 30 defined by stepped marginal edges adapted to fit the peripheral formation of the hub 22 when disposed in operative straddling relation thereto. As in the first described illustration exemplifying the present invention, the marginal portions 32 and 34 defining the said notch 30 of these blades are bent in offset relation to the general plane of the blades and are provided as at 36 and 38, respectively, with flanges which are disposed in substantial parallel relation to the plane of the outside radial faces of the hub 22 when the said blades are disposed in operative relation to said hub. The flanges 36 and 38 provide means whereby the blades may be fastened to the hub 22, as by rivets, welding or in any other desired manner.

As in the previously described embodiment of the invention, the particular connection for the blades in this assembly readily lends itself to all of the advantages which are characteristic of the present invention. In addition the blades as shown are formed to simulate an aerofoil section to secure the advantages of such formation in a device of the type herein illustrated.

In Figures 5, 6 and 7 is disclosed a further alternative form of construction for an axial flow fan possessing the desirable characteristics of the present invention, the same being shown as comprising a plurality of blades 40 mounted upon a supporting element 42 which, in accordance with the disclosure, comprises an annular ring-like member serving as a medium of attachment for the blades to a flanged drum or fly wheel such as 44, as by means of the bolts 46, the said ring-like member 42 being recessed as at 48 to fit over the periphery of the said flanged drum or fly wheel 44. The blades 40 of this embodiment are of similar construction and are of a type intended for heavy duty. The connection between the blades 40 and the ring-like supporting element 42 conforms generally to the connections between the blades and supporting elements of the previously described assemblies, and involves the provision of a notch 50 adjacent the inner end of the blade to provide the marginal portions 52 and 54 adapted to straddle the ring-like member 42.

In this particular embodiment marginal portion 54 is bent into offset relation to the main part of the blade 40 so as to have line contact with one surface of the ring-like member 42, much on the order of the line contact existing between the blades and supporting elements of the previously described structures. The marginal portion 52, however, is shown as being ex-

tended laterally to form a tab 56, which is offset in curved relation to the marginal portion 52 as at 58 whereby the outer marginal edge 60 of the said tab 56 is in contacting relation with the face 5 of the ring-like member 42. To complete the connection between the blades and the ring-like member 42 the portion 54 may be secured in position as by welding or the like, and the tab 56 may be secured as by means of welding along the marginal edge 60 only, or if desired additional welding may be effected along the marginal edge of portion 52.

As will be noted from Figure 7 of the drawings, that portion of the blade between the notch 50 and the edge 60 of the tab 56 abuts the periphery of the flanged drum or fly wheel 44 whereby air is prevented from being drawn up behind the blade, thus increasing the efficiency of a blade of this type.

The particular provision of a tab as illustrated in Figures 5, 6 and 7 provides for additional rigidity for the blade and permits of the formation of various side and bottom pockets which might, under many conditions, be desirable to increase the efficiency of the fan by preventing the radial flow of air during its operation. Such tab formation for the blades increases the line of attachment of the blade to its supporting element to further resist the stress and bending moments to which the same may be subjected, and further lends itself admirably to the provision of attaching the blades at one or more points to the supporting element or to one another. While this embodiment is merely illustrative of the tab formation for the blades in an assembly as contemplated by the present invention, nevertheless, if desired, oppositely opposed tabs could be provided such, for example, as would prevail should the blade 40 be of greater width and the marginal portion 54 be formed with a tab corresponding to tab 56. As in the other illustrative embodiments of the invention, the blade 40 is curved to provide an aerofoil section to facilitate the uniform flow of air from the device.

The fundamental inventive concept as hereinbefore disclosed, lends itself admirably to modified constructions such as shown in Figures 8 and 9 of the drawings, to provide interlocking engagement between the fan blades and the central blade supporting element. In this further illustrative embodiment of the invention the assembly includes the central blade supporting element 62 formed with a central bearing 64, whereby the impeller may be suitably mounted upon and secured to a shaft, such as shaft 8 of the first described embodiment. The central supporting element 62 of this construction is further characterized as being provided with an enlarged rim forming part 66, providing the inner annular shoulders 68 and 70 disposed on opposite sides of the main part 72 of the said supporting element.

Mounted upon the periphery of the central supporting element 62 is a plurality of fan blades 74 constructed much on the order of the fan blades of the previously disclosed structures, and which are further formed with the slots 76 adjacent their inner ends. The slot of each of these blades is formed by the tabs 78 and 80 to provide an enlarged opening 82 and a diverging slot portion 84. These tabs 78 and 80 are provided with the lugs 86 and 88 extending into the slot 76, and which are adapted in one position of the blade to interlockingly engage the shoulders 68 and 70.

The present assembly is particularly charac-

terized by virtue of the formation of the slot 76, which is of such a construction that the tabs 78 and 80 may be moved into straddling relation with respect to the supporting member 62 when the blade is in one angular position with respect to said supporting element, but which provides for interlocking engagement of the lugs 86 and 88 with the shoulders 68 and 70 when the blade is twisted into its final operative position with respect to the supporting element 62. As in previously described assemblies, the tabs 78 and 80 have contacting relation with the main part 72 of the supporting element, as at 90, and the said blades may be secured in such operative relation to the supporting element by means of a weld joint at the point of contact therewith. It is, of course, understood that the tabs 78 and 80 may be formed to provide the additional features of construction which have been more particularly disclosed and described in the structures of Figures 1 to 7.

While Figures 8 and 9 are illustrative of a certain interlocking relation between the blades and the supporting element, it is to be understood that all of the advantages of this type of structure may be secured by the provision of slots or grooves formed on the supporting element 62, providing shoulders adapted to be engaged by lugs of the blades to interlock the same together. The interlocking relation of the blades and supporting element has the advantage of increasing the rigidity of the fan assembly as a whole, and may be a desirable structure where the assembly is subjected to particularly heavy duty during its operation.

While I have herein described and upon the drawings shown illustrative embodiments of the invention, it is to be understood that the invention is not limited thereto but may comprehend other constructions, arrangements of parts, details and features without departing from the spirit of the invention.

I claim:

1. An axial flow fan comprising a central blade supporting element having adjacent its periphery, 45 opposed side surfaces disposed in substantially parallel planes, a plurality of blades formed from metal plates connected to said surfaces and having their fluid impelling surfaces angularly disposed with respect to the plane of rotation of said element, the connection between each of said blades and said element being characterized in that a slot is provided in the base of each blade in such manner as to provide anchorage sections on both sides of said slots, said anchorage sections being mounted in straddling relation with respect to the periphery of said element and having their slot defining edges disposed in abutment with the opposed surfaces of said element, said anchorage sections extending in opposed 60 relation peripherally whereby to dispose said edges in substantially parallel planes to provide

for substantial line contact thereof with the surfaces of said element when said blades are mounted angularly on said element and means for securing said anchorage section to said element.

2. An axial flow fan according to claim 1, in which the anchorage sections are bent out of the general plane of said fluid impelling surfaces from adjacent the end of said slots.

3. An axial flow fan according to claim 1, in which the slots increase in width toward the open end thereof and said anchorage sections are bent out of the general plane of said fluid impelling surfaces from adjacent the end of said slots.

4. An axial flow fan according to claim 1, in which one of said anchorage sections is extended peripherally of said blade supporting element to provide a tab having an outer edge disposed substantially in the plane of the edge of said anchorage section defining said slot and adapted to have substantially line contact with one of the surfaces of said element.

5. An axial flow fan according to claim 1, in which one of said anchorage sections is extended peripherally of said blade supporting element to provide a tab of curved formation having its outer edge disposed substantially in the plane of the edge of said anchorage section defining said slot and adapted to have substantially line contact with one of the surfaces of said element.

6. An axial flow fan according to claim 1, in which said supporting element and blades are formed with shoulders interengageable when said blades are disposed in angular relation to said supporting element.
